2 Claims. (Cl. 51—219)

1

This application is a continuation of my co-pending application Ser. No. 506,695, filed October 18, 1943, now abandoned.

The ordinary twist drill which is nearly always used in drilling holes in metal and is commonly used for drilling holes in many other materials must be ground very precisely to function at its best. The hand grinding or sharpening of these drills requires a very high degree of skill. Not only are the manipulations of the drill against the grindstone complex, but the operator must also be able to exercise his judgment accurately as to the desired angles and variations thereof and the uniformity of the sides. Very complex drill grinding machinery has been developed and used extensively. Not only are these machines extremely expensive, but they require skilled operators.

The problem of drill grinding is complicated by the desirability of increasing the clearance behind the cutting edge from the periphery of the drill towards its axis. The end or point surfaces of the drill, those two surfaces at the end of the helical lands are called the heels. The ordinary drill has two lands separated by two flutes and hence two heels. The front edge of each heel forms a cutting edge or lip of the drill. It is obviously necessary for the heel to be ground off enough to provide a clearance angle behind the cutting edge so that the heel will not ride on the surface of the metal at the bottom of the hole being drilled and prevent the cutting edge from biting into the metal. If the clearance angle is too great, the drill is excessively weakened and the cutting edge will be chipped off in service.

It follows that although it is necessary to provide sufficient clearance to allow the cutting edge to bite into the metal, the clearance angles should not greatly exceed this requirement or the drill will be weakened without any corresponding benefit.

The theoretical clearance angle is considerably greater near the axis of the drill than near its periphery. The reason for this will be apparent by contemplating the path of movement of two points of the cutting edge of the drill, one at the periphery and one adjacent the central web of the drill. For example, let us assume a one inch drill and consider a point at the periphery and a point .1 inch from the axis of the drill. If the

2

drill is fed one-thousandth of an inch per revolution, both points move into the metal being drilled one-thousandth of an inch each revolution but the peripheral point, in advancing this one-thousandth of an inch, moves a peripheral distance equal to the circumference of a circle of one inch diameter, namely 3.1416 inches. The point .1 inch from the axis, on the other hand, has a peripheral movement equal to the circumference of a circle of .2 diameter, namely .6283 while advancing its .001 inch. Thus it is seen that the inner point advances 5 times as steeply into the metal as the outer point and hence it would seem that it must have 5 times the clearance angle behind it in order that the movement of the cutting edge can bite freely into the metal. However, the metal adjacent the cutting edge is naturally subject to some elastic distortion under the pressures applied to them and this distortion may be fairly uniform along the entire cutting edge. As a result of allowing for this elasticity, the clearance angle required at the inner point is in fact not nearly 5 times as great as at the periphery and a great deal more clearance must be allowed at both points than would be indicated by the gradual rates at which they move into the work. Nevertheless the fact remains that a considerably larger clearance angle is desired near the center of the drill than near its periphery.

This complicated shape has been obtained heretofore by considerable manipulation of the drill on the grindstone, this manipulation being either manual or by more or less automatic machinery. The more complex shape described has been obtained in a variety of ways, one of which has involved moving the drill across an edge of a grindstone so that it was differentially ground while rotating the drill at the same time. This, of course, only took care of one land of the drill and it was necessary to go through the whole complicated movement with the drill shifted 180 degrees between times in order to grind the other land to match.

According to the present invention, this complicated movement of the drill which requires either special skill or special machinery or both is avoided. The drill may simply be pressed with little or no rotation against a special grindstone, withdrawn, rotated 180 degrees about its axis

and again pressed without rotation against the grindstone. The shape of the heel surface is determined accurately, uniformly and without the exercise of any operating skill by the predetermined shape of the grindstone and the predetermined positioning of the drill. In other words, the drill is contour ground. Prior to this invention, the provision of the complex shape heretofore described without manipulation of the drill would have been considered impossible. It is accomplished according to the present invention simply by pressing the heel surface to be ground against an inside conical surface of a specially contrived grindstone.

An unskilled operator could be trained quickly to do a fairly good job of drill sharpening by pressing the drill against this grindstone by hand. However, the extremely simple movement of the drill permits the provision of a very simple device for holding the drill in the proper position and shoving it against the grindstone with greater accuracy and uniformity than would be possible in holding the drill by hand. This holder has been worked out to be adapted to a large variety of sizes of drill even though drills of different sizes should be centered at different positions with respect to the grindstone. Adjustment is also provided for varying the clearance angles according to the work to be performed.

Additional objects and advantages of the invention will be apparent from the following description and from the drawings in which

General description

In accordance with this invention, a special grindstone 11 is provided having an internal conical surface 12. This grindstone is carried and driven by the shaft of a motor 13. A drill 14 is sharpened by simply pressing the successive surfaces to be ground against the internal conical surface 12. Of course proper positioning of the drill is important. In the ordinary drill, there are two surfaces to be ground, these surfaces being the ends of the two lands 16 and 17. These end surfaces are called the heels. One of them is seen in Fig. 4 and is numbered 18.

It is, of course, important that the two heels be ground evenly as well as that each have the proper shape. According to this invention, the drill is pressed to a given position while one heel is being ground, then backed away, rotated 180

degrees and pressed to the same axial position while the other heel is being ground. This ensures uniformity between the two heels and the positioning of the drill on the internal conical surface of the stone ensures proper shaping of each heel. Proper positioning of the drill in the two positions is ensured by a holding and manipulating unit 21 which can be much more simple than any prior drill sharpening apparatus because of the simple movements of the drill which are sufficient for accurate grinding, according to the present invention.

The drill is accurately positioned in the unit 21 by placing it against a guide 22 which is swung into position as shown in dotted outline in Fig. 2. During the insertion of the drill, the handle 23 (which moves chuck 24 in cradle ring or carriage 25) would be held by lock 28 in the position shown in Fig. 1. The chuck jaws 26 are tightened on the drill while the parts are thus disposed.

The guide 22 is swung out of the way, the handle 23 is moved to the intermediate position shown in Fig. 2, and the entire unit 21 is slid along base 27 (Fig. 8) into operating position, predetermined as described below. The handle 23 is then swung to the right or left. Approximately at the end of the slot 29, the slot curves forwardly as shown at 30 so that moving the handle as far as it will go to the left also pushes it and chuck 24 forwardly. The handle 23 is rigidly mounted in chuck 24 which is rotatable and longitudinally movable in ring or carriage 25. Thus as the handle is swung to the left, and pushed forwardly by the curve 30 in slot 29, this presses the drill 14 against the internal conical surface of grindstone 12, thus grinding one heel of the drill. The handle 23 is then swung all the way to the right where the other end of the slot is also shaped as shown at 30. This rotates the drill 180 degrees so as to present the other heel to the internal conical surface 12 of the stone and to press it against the stone to the same axial position as before so that the other heel of the drill is ground to match the first heel.

Theory of drill grinding

The proper grinding of a drill is perhaps most evident in the larger sizes where a properly ground drill will cut two uniform coiled shavings 36 from the metal 37 into which it is being uniformly fed. These coiled shavings (or chips, as they are called in the art) are cut from the metal by two cutting edges 38 forming the front edges of the heels 18. In order for the cutting edges to bite into the metal being drilled, it is, of course, necessary that the remainder of the heel behind the cutting edge have sufficient clearance with the metal at the bottom of the hole so that the heel surface will not rest on the bottom of the hole and keep the cutting edge from going deeper. Since the drill is being constantly advanced by the feed thereof, the cutting edges are constantly moving more deeply into the metal with a result that the surface at the bottom of the hole is of generally convolute shape. If the heel surfaces of the drill had the same convolute shape as the bottom of the drill hole, they would rest with equal pressure at all points. Of course it is desired to concentrate the pressure at the cutting edge and hence the heel should have a greater pitch or clearance angle than the pitch of the convolute formed by the bottom of the hole.

If we refer to Fig. 4, enlightening comparisons may be made between the movements of the point A and the point B, and between the clear-

ance angle required behind each. Let us assume that the point A is at the periphery of the drill and the point B is near the axis—say one-fifth of the distance out to the periphery. As the drill is fed, both points move into the metal and the same distance for each revolution of the drill. In a peripheral direction, however, the point A moves five times the distance that the point B moves. It follows that since the point A moves five times the distance that the point B moves for the same advance into the metal, the point B has a pitch or slope of movement five times that of point A. Likewise the slope of the helix described by point B along the bottom surface of the hole is five times as steep as the helix described by point A. It follows that, ignoring distortion of the metal, the clearance angle of the heel 18 must be five times as steep behind the point B as behind the point A. In fact, the resilient distortion cannot be ignored and hence the clearance angle does not need to increase inwardly nearly as rapidly as would be indicated by these ratios. Nevertheless, a greater clearance angle is required near the axis of the drill than at the periphery.

It is not practicable merely to provide along the entire heel surface 18 the maximum angle of clearance that is required because this would unnecessarily weaken the cutting edge and cause it to chip off in service.

It is evident from the foregoing that there are important requirements as to the amount of clearance angle and as to the increasing of the clearance angle inwardly from the periphery of the drill. This does not mean, however, that there can be no departures from one theoretical shape. The shape which with the material being drilled would just barely provide clearance above the bottom of the hole might theoretically be the best shape but in fact there are probably no objections to any variations between this shape and the higher clearance angles at which chipping of the cutting edge begins to occur. Furthermore, there is considerably more leeway quite close to the axis where the areas and torque arms involved are small and where there is relatively little metal that has to be removed in drilling the hole. The clearance angle desired varies according to the material to be drilled, the rate of feed and perhaps other considerations. The drill shown in Fig. 4 illustrates a very common clearance in which a line from the point A to the point where the land joins the heel and the flute at the edge opposite the lip forms a 12 degree angle with a plane perpendicular to the axis of the drill. This is generally referred to as a 12 degree clearance although in fact, the clearance immediately adjacent to the point A is much less than 12 degrees. For the purpose of comparison, the clearance angle at the point B has been indicated as being 23 degrees. Again, the clearance angle immediately behind point B may be less than the 23 degrees there indicated. These clearance angles, as commonly referred to, mean the apparent overall angle. However, a more common way of judging the clearance at the more central portions of the drill can be seen with reference to Fig. 5. Generally speaking, the angle between the cutting edge 38 and the connecting edge 39 crossing the dead center of the drill increases as the clearance near the axis increases. It is common to provide clearance at the central portion of the drill such that this angle between edges 38 and 39 is from 120 to 135 degrees.

The angle of the cutting edge with the axis of

the drill is also important, although the 59 degree angle illustrated in Fig. 6 is very much more common than any other angle. Naturally it is also important to have the two cutting edges identical or one will do more work than the other, or the drill may drill off center and drill a hole that is too large or irregularly shaped.

Grinding on the conical stone

The shape of the drill surfaces in the various respects discussed above can be predetermined in accordance with the present invention by selecting a stone having a suitable angularity of its cone and by properly selecting the position of the drill as it is pressed against the internal conical grinding surface. It is not meant to imply that the conical grinding surface will shape the heel to an accurate convolute. It may, however, come closer to providing a theoretically perfect surface than any previous comparable machine and closer than is achieved by the most skilled hand-sharpening, except in rare instances of good luck. At least tests have shown that it comes within the permissible limits of departure from a theoretically perfect surface.

Any internal grinding surface may be used to obtain the advantages of this invention to some extent. In fact, if point shapes not now common were desired, any internal grinding surfaces of progressively decreasing radius would be within the range of this invention. The accuracy and simplicity of this invention may possibly result in the production of drill shapes even more desirable than present common drill shapes and, of course, the invention can be used to produce a wide variety of shapes whether better than common drill shapes or not. It is preferred, however, at least for the present, that a surface be chosen, and a positioning of the drill thereon, such as will approximately reproduce conditions now more or less regarded as standard.

For the convenience of those wishing to practice the invention, one cone size and drill positioning thereon that have been found satisfactory will be described, but it should be recognized that this is just one of the many ways in which the resulting shape can be produced or closely approximated.

One cone size which has been found very suitable is a cone having a vertex angle of 82 degrees. In other words, an element of the cone (a line extending from the vertex along the cone surface in an axial plane) makes an angle with the axis of 41 degrees.

Although cones of almost any angle can provide some of the advantages of this invention, those between approximately 59° and approximately 118° have some advantages for drills having lip angles of 59°. A smaller angle than 59° at the vertex will cause the body of the drill to strike the cone at its periphery in moving the drill point close to the vertex. A larger angle than 118° may not closely approximate the conventional surfaces.

The proper positioning of the drill on such a surface will depend somewhat on the size of the drill. It has been determined, however, that when only one type of point is desired, good results can be obtained by keeping all adjustments constant except the distance of the drill from the axis of the cone. Hence the only variation in positioning that needs to be made for different sizes of drills is to move the dead center of the drill along an element of the cone and hence the chuck may be mounted to move in

a direction parallel with the cone element on which the drill is centered, and no other adjustment will ordinarily be necessary. This cone element of the cone may be referred to as the chosen element.

With the conventional surface in which the lip has an apparent angle of approximately 59° with the axis of the drill, the lip can be placed approximately parallel to the chosen element of the grinding cone and the drill positioned with its axis forming an angle of 59° with said element. The lip is then bound to have the desired angularity with the axis of the drill. Speaking more accurately, it should be noted that a line or element of the heel surface extending from the dead center and which lies against the chosen element of the cone, is bound to make an angle of 59° with the axis of the drill in accordance with conventional practice.

The angle of clearance is determined in part by the angle which the axis of the drill makes with that plane which includes both the axis of the drill and the chosen element, it being assumed again that the lip of the drill is approximately in this plane. In Fig. 6, this plane has been identified as axial plane A and its intersections with the cone have been shown. The drill axis has been shown in Fig. 6 intersecting the chosen element 41 at a point C. This is the point at which the dead center of the drill is placed. One approximate position of the surface being ground has been shown in dotted lines. The lip 38 is here represented as lying approximately along the element 41 from slightly above point C outwardly on the cone to the point where it intersects the element.

As seen in Fig. 6, the drill axis makes a minimum angle of approximately six and one-half degrees with axial plane A. In other words, if the axis is projected perpendicularly onto plane A, the projection will form an angle of $6\frac{1}{2}^\circ$ with the drill axis. Surprisingly, this $6\frac{1}{2}^\circ$ inclination of the drill axis gives a much larger apparent clearance angle, and it is the apparent clearance angle (measured with reference to point A in Fig. 4) which is customarily made 12° for the so-called 12° clearance. Hence the surface of a drill positioned as described will very closely match the conventional surfaces.

This positioning of the drill does not make the central angle shown in Fig. 5 quite as large as is generally desired. Hence it is at present preferred to rotate the drill about its axis until this angle is the desired size. 120° – 125° is at present preferred for this angle because it gives the best drilling results.

For very close matching of conventional surfaces, the drill's dead center C should be very carefully positioned along the chosen element 41. Analysis has indicated that a one-inch drill should have its dead center C positioned approximately .415 inch long the element from the vertex and that for each one-eighth inch increment in drill size, the point C should be moved along the element .05 inch. However, the drill holding chuck is preferably readily movable along the element and the proper positioning for any drill size may readily be determined by the results, the variations along the element being such as to keep the apparent clearance angles constant.

When a drill is quite different from the shape to which it is to be ground, it is sometimes desirable to preliminarily increase the distance from the vertex so that the drill will not, on account of

its odd original shape, strike the far side of the cone.

Although the positioning of the drill described has been chosen for giving close approximation to given surfaces, it should be recognized that some variations in positioning may later be preferred in order to match more closely some one part of conventional surfaces or some one part of a theoretically perfect surface.

10

Drill holding unit

The general nature of the drill holding unit 21 has already been described. However, it has a number of special features which warrant further attention.

It will be observed that the cradle ring or carriage 25 is pivoted at 46 about a pin 47 whose axis intersects the axis of chuck 24 and is parallel with, and during grinding coincides with, the chosen element 41 of the cone. Of course the axis of pin 47 could be aligned with any element of the cone and whatever element it is aligned with would become the chosen element, the axis of the chuck 24 intersecting the axis of pin 47. The pin 47 is preferably inclined at an inclination of about 16° degrees, thus choosing the element of the cone which has the same inclination. The purpose of this is merely to make the axis of the chuck and hence the axis of the drill approximately horizontal as a matter of convenience.

It will be observed that the pin 47 is carried by bracket 48 forming an extension of pedestal 49. Secured at the opposite side of pedestal 49 is an arcuate brace 51 which is shaped concentrically about the axis of the pin 47. This arcuate brace is seen best in Fig. 8. As seen in Figs. 7 and 8, the cradle or carriage 25 is provided with an extension 52 straddling the arcuate brace 51 and having a lock screw 53 for locking the cradle at any pivoted position about the pin 47. This adjustment determines the clearance angle of the drill and in each shop will ordinarily be set for the clearance angle desired by that shop. The brace 51 may be calibrated with the actual or apparent clearance angles which will result from each setting.

The pedestal 49 is slidably carried by slide plate 56, seen best in Fig. 8. The slideway of this plate is parallel to the chosen element of the cone and hence parallel to the pin 47. The result is that movement of the pedestal 49 on slide plate 56 adjusts the position of the drill along the element of the cone without changing anything else. The position of the drill may be further adjusted by movement of crank 85.

The slide plate 56 is in turn slidably carried by the base 27 with a movement which is axial of the grindstone. The movement of the unit toward the grindstone is limited by stop screw 58 which is adjustable to make accommodation for variations in thickness of the grindstone 11 and for wear of its grinding surface. Of course a lock nut 59 or other such device is provided.

Some means should also be provided for holding slide plate 56 against stop screw 58. Any biasing or clamping device could be used. In the illustrated form, it is a handle-operated clamp which is loosened by a movement away from stone 11 so that a continuation of this movement will move the unit away from the stone for removing one drill and inserting another.

Chuck

Because this apparatus is adapted to grind a wide variety of drill sizes, it is desirable to have

a chuck which will be capable of holding such a wide variety of sizes. Although the chuck illustrated in Figs. 9 and 10 has been specially devised for the purpose of the present invention, it is also suitable for numerous other purposes and in fact is highly advantageous whenever a wide variety of sizes or rodlike members is to be held.

The accommodation of a wide variety of drill sizes was complicated by two factors. One is the irregularity in the shape of the drills, not only due to the presence of flutes thereon but also because each flute is provided along one edge with a rib 61 which leaves clearance between the rest of the drill and the sides of the hole which has been drilled. The other factor which complicates the problem is the vital necessity of exactly centering all of the drills in order that when it is turned 180 degrees about its axis, the second heel will be ground exactly as was the first.

According to the present invention, the chuck requirements have been solved by using two long sliding jaws which have staggered interfitting V-notched teeth 62 and which slide in a V-shaped recess in the chuck cylinder 63 which supports the jaws 26 and presses them toward one another along a substantial portion of their length.

The staggered positioning of the teeth of one jaw with respect to those of the other is best seen in Fig. 7. These teeth are preferably long enough to accommodate whatever maximum size of drill is to be handled, say one and one-half inches. The recesses between the teeth are preferably deep enough to accommodate the teeth of the opposing jaw until the jaws have been completely closed so that they can hold a very small drill. Of course this depth may be slightly less if, say, nothing smaller than one-eighth inch is to be ground with a particular machine.

Of course the jaws may be slid in the chuck cylinder 63 in any convenient manner. In the illustrated forms, each jaw is moved by a pin or key plate 66 which is pressed in end portions of a slot 67 in a block 68. To the block 68 in Figs. 9 and 10 is swivelled a rod 69 which is threaded to a stationary block 71 so that turning the handle 72 moves the sliding block 68 forwardly and rearwardly which in turn moves the jaws 26 forwardly or rearwardly in their V-shaped recess. The parts are held in proper position by cover plate 73 which also serves to brace the sides of the chuck cylinder 63. On rearward movement, jaws 26 are drawn apart by interaction between splines 74 and grooves 76.

The movement of block 68 is accomplished slightly differently in the other figures, a worm rack 75 being secured thereto and being moved by an internally threaded ring 77 which is journaled at the end of chuck block 63.

After the chuck cylinder 63 is slid into the cradle 25, the handle 23 is screwed into the chuck cylinder 63 for operating the same.

The drill is accurately positioned within the chuck by latching the chuck in the position shown in Fig. 1 and holding the drill lip against the corner 78 of gauge 22 while the chuck is tightened. This determines both the axial position of the drill and its angular position about its axis. For the latter purpose, the sense of touch may easily be relied upon for getting the lip flat against the underface 79 of the gauge. It will be noticed that underface 79 is very narrow at one end thereof. The reason for this is so that in small drills, it will not strike the other land than that against which the gauge is being applied. It is not necessary to provide a stop for the gauge

in its active position as it will drop down on the lip of the drill.

The depth of cut is determined by thumb screw 81 carried by a bracket 82 on cradle 25 which limits the forward position of chuck 24 as the handle 23 is pressed down in curved end portion 39 of slot 29. During positioning of the drill in the chuck, thumb screw 81 is turned to its zero position, after which it is turned to the depth of grinding desired. Alternatively, the latch 28 could be made self-sufficient for holding handle 23 in the zero position and stop screw 81 could then be left in a desired position for depth of grind.

The face 78 of gauge 22 determines the final position of the lip of the drill. At the present time, it is preferred that this face will lie at an angle which, as viewed from a direction parallel with the axis of the drill, appears to slope 12° above the horizontal upwardly in a direction away from the axis of the drill. Since the gauge pivots to slightly different positions for different sizes of drill, there will be slight variations in this slope, but not enough to be objectionable. This slope makes the angle shown in Fig. 5 approximately 123° and the slight variations due to size of the drill do not carry this beyond satisfactory limits. Anything from 120° to 125° is believed to be highly satisfactory and many people believe that the angle can be as large as 135°.

Although this chuck and the cradle or carriage and slide arrangements described are especially suitable for the purposes of the present invention, it is recognized that in pressing the drill against the internal grinding surface in accordance with this invention, a wide variety of holding devices may be used, and additional adjustments may be desired. For example, it may be desirable to have an adjustment for the angle between the axis of the drill and the axis of the pin 47. Adjustments may also be provided for position of the motor. For example, it may be found to be desirable to raise and lower the motor, or move it in a direction perpendicular to the chosen element and tangent to the cone in order to adjustably position the lip of the drill closer to the chosen element, or slightly therebelow to give a greater increase of the clearance angle inwardly in the region close to the cutting lip.

It is quite possible that other positions for the pin 47 and perhaps other inclinations for the sliding action of bracket 49 will be found desirable. For example, there would be some advantage in shifting the pin 47 to a position approximately coinciding with an extension of the corner 78 so that change of clearance angle could be made about an axis approximately coinciding with the lip of the drill, as can be done when the drill is in the position shown in Fig. 6.

It is desirable that the grinding surface be kept clean during grinding. This requires special attention because the stone is not self-cleaning inasmuch as the internal angle is such that centrifugal force tends to cause the debris to cling against the rough conical wall instead of being thrown out from the stone. The stone may be kept clean by a continuous blast of air liberated near the apex. It is preferred to use a vacuum cleaner with a nozzle extending along an element of the cone and reaching close to the apex by passing between the drill and the cone surface. The wear on the stones is not excessive. Usually, various sizes of drills will be ground and their wear will be spread over different areas of the cone surface. Slight departures of a true cone are not materially objectionable and do not cause

11

any noticeable difference in the ground surface. As often as may be desired, however, the stone may be dressed to an accurate conical surface by inserting a diamond-tipped dressing tool in the chuck, adjusting the holding unit for the proper depth of cut in the stone and turning the handle 85 rapidly as the motor drives the stone to move the diamond tip along the length of an element of the new surface. It will be observed that this accurate parallelism between the chosen element of the cone and the movement of the tips of the drills held in the chuck so that turning the handle 85 to position the chuck properly for different drill sizes will merely move the drill along this element without altering the depth of grind for which the thumb screw 81 has been set.

Analysis has indicated that departures of shape of the surfaces ground in the foregoing manner are extremely slight as compared with a theoretical surface which would be generated by movement of the cutting lip along a helix of the desired pitch. For example with the grinding position shown in Fig. 6, calculations have indicated that the maximum departure from the theoretical surface is only .03 inch while the departure along the cutting edge is even less. Of course the ultimate test is in satisfactory drilling and that test has been met by the products of this invention.

From the foregoing, it is seen that a new method of grinding drills has been devised in which the entire surface of one heel of the drill can be ground at once without any manipulation of the drill other than simply pressing it against the internal conical surface of the newly devised stone. Suitable apparatus has been provided for practicing this method in a simple manner and with adequate adjustability, but with extreme uniformity for any adjustment.

I claim as my invention:

1. Drill sharpening apparatus including a grindstone having an internal conical surface centered about its axis and a drill holder including a carriage, a chuck slidably and rotatably mounted in the carriage, means for initially correctly positioning the drill in the chuck coaxially

5
10

15
20
25
30
35

therewith, means for swinging the chuck about the common axis to different positions to place first one heel of the drill and then the other in grinding position against the said internal surface of the grindstone with the center of the drill point displaced from the axis of the stone, and for advancing the chuck axially to a predetermined final position, and means for mounting the carriage tiltably about an axis approximately coinciding with the cutting edge of the drill in the position to which it is finally ground whereby the clearance angles behind said cutting edge may be adjusted while leaving other factors unchanged.

2. Drill sharpening apparatus including a grindstone having an internal conical surface centered about its axis and a drill holder including a carriage, a chuck slidably and rotatably mounted in the carriage, means for initially correctly positioning the drill in the chuck coaxially therewith, means for swinging the chuck about the common axis to different positions to place first one heel of the drill and then the other in grinding position against the said internal surface of the grindstone with the center of the drill point displaced from the axis of the stone, and for advancing the chuck axially to a predetermined final position, and means for mounting the carriage tiltably about an axis approximately parallel with the cutting edge of the drill in the position to which it is finally ground whereby the clearance angles behind said cutting edge may be adjusted.

MELVIN DOUGLAS.
